UNITED STATES PATENT OFFICE.

WILLIAM H. HUNTER, OF DETROIT, MICHIGAN.

AEROPLANE.

Application filed March 12, 1923. Serial No. 624,615.

This invention relates to aeroplanes and the invention consists in the structural features and arrangement of parts hereinafter described and illustrated in the accompanying drawings, wherein:—

Figure 1 is a plan view of the improved aeroplane;

Figure 2 is a view of the same in side elevation;

Figure 3 is a perspective view of the same;

Figure 4 is a cross section view of a brace member;

Figure 5 is a vertical cross section on line 5—5 of Figure 2;

Figures 6 and 7 are respectively a vertical and a horizontal sectional view of the rudder mounting.

In these views, the reference character 1 designates a fuselage having the pair of forward supporting wheels 2 and having a rear supporting and steering wheel 3. 4 designates a wing member mounted at a suitable elevation above the fuselage by brace frames

5^a. Converging arms 5, laterally extending from the fuselage, support bearings 6 for a pair of parallel shafts 7, symmetrically disposed with respect to the longitudinal axis of the fuselage. Upon the forward ends of said shafts, the pulling propellers 8 are mounted, and rearwardly thereof, the shafts carry annular propulsion elements 9 having diagonal vanes 10, said elements 9 exercising both a lifting and pulling effort.

11 35 designates a transversely mounted shaft having drive connections to the shaft 7 through bevel gears 12. 13 is an engine suitably carried by the fuselage 1 and having a drive connection 14 from its shaft 15 to the transverse shaft 11.

Front and rear steering stems 16 and 16' project respectively forwardly and rearwardly from the fuselage, said shafts having a ball and socket universal mounting upon the fuselage, as indicated at 17. The stems 16 and 16' carry vertical rudder elements 18 and horizontal rudder elements 19. Cables 20 are attached to the rudder elements 18 and extended oppositely from said elements 50 upon the fuselage to a steering wheel 21 mounted in suitable proximity to the seat 21', the arrangement being such that said elements 18 respond reversely to rotation of said steering wheel. Similarly, cables 22 are 55 extended from the rudder elements 19 to a steering wheel 23 and subject said elements

to reverse angular movement upon turning of said wheel.

The wheels 2 are of disk type and are exteriorly provided with substantially radial vanes 24. A drive connection to said wheels is established, as indicated at 25, the upper portion of said wheels being hooded, as indicated at 26, so that a propulsion value is derived from said vanes when the aeroplane 60 is in flight. The fuselage 1 is of a boat type and when the same rests upon water, propulsion is derived from the vanes 24.

For travel of the vehicle either upon land or water, the small rear wheel 3 is utilized for steering, said wheel being carried by a vertically journaled stem 27 having the steering handle 28. Preferably the outer end portions of the wings are slightly curved, as best seen in Figure 1, so as to 70 conform somewhat to the shape of a bird's wing.

The front and rear rudders, controlled in unison, render the vehicle more quickly and positively responsive to any steering effort.

80 The various posts 28^a, which connect the fuselage and wing member of the described aeroplane, are V-shaped in cross section, as is best seen in Figure 4, and cables 29 or other flexible tensioning elements are extended within said posts between the wing member and fuselage. These cables reinforce the posts and in case of breakage of any one thereof tend to maintain the proper registering relation of the broken ends. The 85 rear stem 16' is provided with upwardly and downwardly projecting pins 30 adjacent the universally supported end of said stem and said pins are respectively terminally connected to control cables 31 and 31^a which 90 lead to foot pedals 32 suitably arranged for control by the feet of the operator. The stem 16' may be rotated to the right or left according as pressure is exerted upon one 95 or the other of the foot pedals 32, the resulting angular shifting of the horizontal rudder elements 19 being utilized to compensate for any tendency of the aeroplane to tip laterally.

100 33 designates a flap pivoted to the front edge of the wing member 4 at an equal distance from the extremities of said member, said flap being angularly adjustable up and down by a lever 34 acting through a link 35 to control said flap. When it is desired to 110 ascend rapidly, the flap 33 is upwardly adjusted to present a surface considerably in-

clined to the air current resulting from the movement of the vehicle.

It is preferred to provide a number of air tanks 36 in the lower portion of the fuselage to increase the buoyancy thereof when resting upon water. 37 are water outlet passages extending through the floor of the fuselage and having their outlet ends closed normally by flap valves 38.

10 What I claim as my invention is:—

1. In an aeroplane, a fuselage, a rudder comprising transverse vanes, means for adjusting said rudder in the plane of either vane, and means for rotating the rudder about the common axis of said vanes.

15 2. In an aeroplane, a fuselage, a rudder mounted upon said fuselage at one end thereof universally movable and rotatable,

and independent means for angularly shifting said rudder for steering purposes and 20 for rotating the rudder to compensate for tip of the aeroplane.

3. In an aeroplane, the combination with a fuselage having a substantially spherical socket in one end thereof, of a rudder for 25 said aeroplane comprising a stem terminally formed with a ball mounted in said socket for universal movement, said rudder further comprising two vanes in substantially transverse planes, cables engaging each of said 30 vanes for effecting movements of the rudder in said transverse planes and a cable engaging said stem for rotating the same.

In testimony whereof I affix my signature.

WILLIAM H. HUNTER.
